UNITED STATES PATENT OFFICE.

GEORGE F. TAYLOR, OF RANDOLPH, MASSACHUSETTS.

CAR-FENDER.

No. 802,361.

Specification of Letters Patent.

Patented Oct. 17, 1905.

Application filed February 13, 1905. Serial No. 245,343.

To all whom it may concern:

Be it known that I, GEORGE F. TAYLOR, a citizen of the United States, residing at Randolph, county of Norfolk, and State of Massachusetts, have invented an Improvement in Car-Fenders, of which the following description, in connection with the accompanying drawings, is a specification, like numerals on the drawings representing like parts.

10 This invention relates to car-fenders, and has for its object to improve the fender illustrated in Patent No. 760,662, dated May 24, 1904, granted to myself and Peter B. Sullivan. The car-fender illustrated in said patent is 15 hinged to the car and is operatively connected with the brake mechanism of the car, so that when an obstacle strikes the nose of the fender and the latter is thrown downwardly the brakes are applied automatically. Said fender 20 also has a suitable spring device for normally holding the fender-nose elevated. In my present improvement I have substituted for this spring device a friction device which operates to normally hold the nose of the fender elevated, but which friction device permits the fender to drop whenever it strikes an 25 obstacle.

In the drawings, Figure 1 is a side view of 30 a car-fender having my improvements applied thereto. Fig. 2 is an enlarged section on the line xx , Fig. 1; and Fig. 3 is a detail of the friction device hereinafter referred to.

3 designates a fender of any suitable or usual construction. Said fender is hinged to 35 the car in any suitable or usual way, it being herein shown as being hinged to a suitable arm 4, projecting forwardly from the car.

5 designates the usual motorman's valve for 40 controlling the air-brakes, 6 designates the exhaust-pipe leading from said valve, 7 designates the pipe leading from said valve to the reservoir, and 8 designates the pipe leading from said valve to the brake-cylinder. The pipes 7 and 8 are connected by a by-pass 9, 45 which has therein a valve 10, which is controlled by the fender. For this purpose a valve-operating lever 11 is shown, which bears at one end against the stem of the valve 10 and at its other end is connected to the fender 50 in any suitable way, as at 12. When the fender is elevated, the valve is normally closed, thereby closing communication between the pipes 7 and 8, except as said communication is opened by means of the motorman's valve 55 5. When the fender is thrown down, how-

ever, and the upper end swings forwardly, said valve is opened, thereby admitting air from the reservoir to the brake-cylinder and applying the brakes. At the same time a valve 14 is closed, thereby preventing the escape of air through the motorman's valve and exhaust-pipe 6 in case the motorman's valve should be set with the exhaust open.

The parts thus far described are or may be as illustrated in the aforesaid patent. 65

In order to hold the nose of the fender elevated, I have provided a friction device which is so constructed that a slight blow against the nose of the fender—such, for instance, as would be occasioned by the fender striking 70 an obstacle—will release the friction device and allow the fender to drop, thereby applying the air-brakes and stopping the car. The friction device I have herein illustrated comprises a pair of spring-jaws 20, which are 75 suitably secured to the bottom of the car, and a locking-lever 21, having at one end a head 22, adapted to be frictionally engaged by the jaws 20. The lever 21 is pivoted to the car in any suitable way, as at 23, and is pivotally 80 connected to a thrust rod 24, which in turn is connected to the fender below the point where it is hinged to the car.

When the fender is swung about its pivot-point 26 the locking-lever 21 is swung into 85 the full-line position, Fig. 1, thereby carrying the head 22 thereof between the friction-jaws. These spring-jaws hug the head with sufficient friction to hold the nose of the fender elevated; but the friction between the jaws 90 and head is such that a slight blow on the nose of the fender—such, for instance, as would be occasioned by the fender striking an obstacle—withdraws the head from the friction-jaws and allows the fender to drop 95 into the dotted-line position. The movement of the fender into the dotted-line position operates to open communication between the pipes 8 and 7, whereby air is admitted from the reservoir to the brake-cylinder, and the 100 brakes are applied.

Projecting from the head 22 are ears or lugs 28, which form stops to prevent the head 22 from being inserted too far between the jaws 20. 105

I prefer the form of friction device herein illustrated for holding the nose of the fender elevated; but this is not essential to the invention, as any suitable form of friction mechanism for this purpose may be employed. 110

Neither is the particular manner herein illustrated of controlling the brakes by the fender essential to the invention, as my improvement may be applied to any fender in which the car-brakes are controlled by the fender.

Having fully described my invention, what I claim as new, and desire to secure by Letters Patent, is—

1. In a car-fender, a fender hinged to a car, friction devices to hold the nose of the fender elevated, said friction devices permitting the fender to drop when it strikes an obstacle, and means operating in conjunction with the fender to stop the car when the fender is moved into its lowered position.

2. In a car-fender, a fender, friction devices to hold the fender elevated from the track,

and brake mechanism for the car controlled by the fender.

3. In a car-fender, a fender hinged to the car, means to hold the nose of the fender elevated, said means comprising a pair of spring-jaws, a locking-lever operatively connected to the fender and having a head to be frictionally engaged by said jaws, combined with brake-actuating mechanism controlled by the fender.

In testimony whereof I have signed my name to this specification in the presence of two subscribing witnesses.

GEORGE F. TAYLOR.
